US0D1038093S

(12) **United States Design Patent** (10) **Patent No.:** **US D1,038,093 S**
(45) **Date of Patent:** **** Aug. 6, 2024**

(54) **STAND FOR DISPLAY DEVICE**

(71) Applicant: **LG ELECTRONICS INC.**, Seoul (KR)

(72) Inventors: **Hyeyoung Hong**, Seoul (KR); **Seungdon Lee**, Seoul (KR); **Yoonkyeong Lee**, Seoul (KR)

(73) Assignee: **LG ELECTRONICS INC.**, Seoul (KR)

(**) Term: **15 Years**

(21) Appl. No.: **35/518,117**

(22) Filed: **Aug. 23, 2022**

(80) **Hague Agreement Data**

Int. Filing Date: **Aug. 23, 2022**

Int. Reg. No.: **DM/223083**

Int. Reg. Date: **Aug. 23, 2022**

Int. Reg. Pub. Date: **Aug. 25, 2023**

(30) **Foreign Application Priority Data**

May 23, 2022 (KR) 30-2022-0020480

(51) **LOC (14) Cl.** **14-03**

(57) **CLAIM**

The ornamental design for a stand for display device, as shown and described.

DESCRIPTION

1. Stand for display device

1.1 : Perspective

1.2 : Rear perspective view

1.3 : Front

1.4 : Back

1.5 : Left

1.6 : Top

1.7 : Bottom

1.8 : Exploded perspective view

1.9 : Reference

1.10 : Reference

The broken lines indicate portions of the article that form no part of the claimed design; the right side view is omitted because it is a mirror image of the left side view; reproduction 1.8 is an exploded perspective view in a state of which the magnet tray is separated from the claimed design; reproduction 1.9 is a front perspective view in a state of which the display device is installed in the claimed design; reproduction 1.10 is a rear perspective view thereof; the broken line showing of the display device in reproductions

(Continued)

1.9 and 1.10 is provided for the purpose of illustrating environmental structure and forms no part of the claimed design.

1 Claim, 10 Drawing Sheets
